SAFETY HARNESS FOR HAND PURSES

Leslie Hill, New York, N. Y.

Application January 21, 1949, Serial No. 72,001

1 Claim. (Cl. 224—28)

1

This invention relates to a safety harness for hand purses.

It is an object of the present invention to provide a harness which will secure a purse to the hand of the wearer and to the wrist and wherein the wrist strap may contain a compact.

Other objects of the present invention are to provide a safety harness for hand purses which is of simple construction, easily applied to the hand and arm of the wearer, inexpensive to manufacture, easy to adjust, and efficient in operation.

For other objects and for a better understanding of the invention, reference may be had to the following detailed description taken in connection with the accompanying drawing, in which

Fig. 1 is a perspective view of the hand purse and the safety harness as the same appears from the inner face of the hand.

Fig. 2 is a perspective view of the purse and harness as it appears on the rear of the hand.

Fig. 3 is a perspective view of the harness removed from the hand.

Referring now to the figures, 10 represents a purse which is of such shape and size as to neatly fit in the palm of the hand. This purse has a slide fastener opening 11 with a slide 12 operable along the opening. Secured to the rear of the purse is a strap 13 having a buckle 14 through which the opposite end of the strap is extended and made secure about the back of the hand. Elevated above the strap 13 and connected thereto by front and back safety straps 14 and 15, is a wrist strap 17 having a compact 18 therein. A buckle 19 of the strap 18 serves to receive the free end of the strap 21 such that the strap 17 can be made secure about the wrist with the compact 18 appearing on the back thereof.

The safety straps are connected between loop members 23 and 24 on the strap 13 and member

25 on the strap 17 and loop portion 26 on compact 18.

It should be apparent that with both hand and wrist straps made secure on the hand and wrist of the wearer and with the fingers extended about the purse, that there is little opportunity for the purse to become separated from the hand.

While various changes may be made in the detail construction, it shall be understood that such changes shall be within the spirit and scope of the present invention as defined by the appended claim.

Having thus set forth and disclosed the nature of my invention, what is claimed is:

15 In combination, a pocketbook having an opening therein, a strap attached to one side of the pocketbook and adapted to be extended about the back of a hand, a second strap adapted to be extended about the wrist of a wearer, and safety straps extending respectively over the front and back of the hand and connected with the hand and wrist straps, and said wrist strap having a compact therein and with one of the 20 safety straps being connected to the wrist strap through the compact.

LESLIE HILL.
